(57) **CLAIM**

The ornamental design for a plant water tray, as shown and described.

DESCRIPTION

FIG. 1 is a top perspective view illustrating our design for a plant water tray disposed in a closed orientation.

FIG. 2 is a bottom perspective view thereof.

FIG. 3 is a top view thereof.

FIG. 4 is a top view of the plant water tray disposed in an open orientation.

FIG. 5 is a front view thereof.

FIG. 6 is a bottom view of the plant water tray disposed in the closed orientation.

FIG. 7 is a front view thereof.

FIG. 8 is a right side view thereof.

FIG. 9 is a rear view thereof.

FIG. 10 is a left side view thereof; and,

FIG. 11 is another top perspective view thereof.

The broken lines in FIG. 11 showing a plant are for the purpose of illustrating environment and form no part of the claimed design.

1 Claim, 8 Drawing Sheets
